FRACTIONATING PROCESS AND APPARATUS

Daniel E. Stines, Plainfield, N. J., assignor to Standard Oil Development Company, a corporation of Delaware

Application April 7, 1932. Serial No. 603,689.

5 Claims. (Cl. 196—132)

This invention relates to improvements in the fractionating of relatively high and low boiling compounds from a mutual solution thereof.

It is an object of this invention to automatically control the reflux of a fractionating column. It is a further object to use the level of reboiler liquid to control the flow of side streams from a fractionating tower.

Other objects will be apparent from the specification and from the accompanying drawing in which latter the figure is a diagrammatic representation of a preferred apparatus for carrying out the invention.

With a preferred embodiment in mind but without intention to limit the invention more than is required by the prior art, the raffinate from a solvent extraction treatment of lube distillate is separated into a fraction comprising a substantially pure solvent and a fraction comprising substantially solvent free petroleum. Such a raffinate may consist of approximately ten percent of the solvent which may be a pure compound such as phenol boiling at 358° F. and 90% petroleum fraction having an initial boiling point of approximately 700° F.

The raffinate is pumped by means of a pump 1 through a line 2 in a furnace 3. In passing through the furnace 3 the raffinate is heated to a temperature above the boiling point of the solvent and most of the solvent is vaporized. The heated raffinate is passed through a line 4 to an intermediate portion of a bubble tower or fractionating zone 5. The bubble tower is provided with a plurality of bell caps and overflow pipes according to the usual construction. The unvaporized portion of the raffinate flows downwardly through the stripping section of the bubble tower. As the raffinate flows downwardly through the bubble tower more and more of the solvent remaining in the raffinate is vaporized by the rising vapors so that the final overflow which is caught upon a pan 6 is substantially free of solvent.

The overflow is delivered from the pan 6 through line 10 into accumulator 11. The overflow is pumped from the accumulator by a pump 13 through a flow controller 14 in a line 15 into a portion of the furnace 3, where the liquid is heated in a reboiler circuit to a temperature in excess of that necessary to supply the additional heat required to heat the feed plate overflow in the bubble tower up to the temperature of the contents of the bottoms pan 6 and to vaporize the phenol in the feed. The partly vaporized discharge from line 15 is released into the bubble

tower 5 below the pan 6 whereby the vapors of the reboiled liquid rise upwardly through the bubble tower and function to strip the low boiling compound from the feed plate overflow. The liquid which accumulates in the bottom of the bubble tower consists substantially of a solvent free lube fraction. This bottoms liquid is removed from the bubble tower through a line 17 and pump 18 at the rate at which it accumulates in the tower bottom. The reboiler pump 13 is flow controlled to deliver the accumulator liquid therethru at a constant rate several times in excess of the rate at which the bottoms are withdrawn from the bubble tower, through the pump 18. The accumulator liquid in passing through the furnace 3 is subjected to a control to maintain a constant temperature at the outlet of the line 15 into the bubble tower. As a consequence, a constant heat input is supplied to the bottom of the bubble tower. The composition of the feed of liquid into the accumulator is maintained substantially constant.

The solvent or low boiling compound is withdrawn overhead from the bubble tower through a line 23 to a series of condensers 24 and 25. The condensed solvent from condensers 24 and 25 is delivered to containers 26 and 27 respectively. A portion of the condensed solvent is returned through a line 28 to the upper portion of the bubble tower to function as a refluxing agent. The remainder of the condensate is withdrawn through a line 29 to a place of storage not shown.

Means are provided for controlling the delivery of reflux through line 28 into the tower. These means comprise a liquid level control 33 in the accumulator 11 which is operatively connected through a line 34 with a control valve 35 in the reflux line 28.

By the procedure described a constant heat input to the bottom of the bubble tower is maintained through the reboiler circuit. This constant heat input together with the preheat circuit heat input is somewhat in excess of the heat necessary to supply the latent and sensible heat which the products have as they leave the bubble tower. This excess heat is balanced by excess reflux liquid returned to the bubble tower through the medium of the liquid level controller in the accumulator which controls the valve 35 in the reflux line. The excess reflux is sufficient to offset the excess heat since it condenses those oil vapors rising from the bottom of the tower which are in quantities over and above the quantity of oil vapors needed to vaporize the unvaporized phenol in the feed. By maintaining the excess

heat balanced by the excess amount of reflux through a fractionating zone whereby heavier liquid the level of liquid in the reboiler accumulator remains constant.

For moderate fluctuations in the quantity and composition of the feed, the excess heat in the reboiling step is either diminished or increased as required by the nature of the fluctuation in feed. If a fluctuation in the quantity or composition of the feed occurs such that more heat is required, then the excess heat is diminished. At that instant the excess quantity of reflux liquid overbalances the excess heat of the reboiler liquid, condenses more oil vapors and causes the accumulator level to rise. The rise in the level of the accumulator liquid causes the reflux valve 35 to be actuated to pass reflux liquid into the bubble tower at a slightly lower rate thereby stabilizing the operation. For initial operation it is necessary to adjust the reboiler pump and thereby the input of heat into the reboiler liquid as indicated by the temperature at the top of the bubble tower.

In a modified form of carrying out the invention a side stream 37 having a valve 38 is provided leading from an intermediate portion of the bubble tower. A line 39 operatively connects the valve 38 with the liquid level controller 33 so that the balance between reboiler heat input and reflux cooling is maintained, during fluctuations in feed volume or composition, by regulating the amount of side stream withdrawn.

While the invention has been described as applied to the treatment of raffinate from a solvent extraction treatment of lube distillate, it will be understood that it is intended to similarly separate compounds from any source having different boiling points.

I claim:

1. The method of fractionating hydrocarbon vapors, which comprises passing the vapors through a fractionating zone whereby heavier constituents of the vapors are condensed, withdrawing uncondensed vapors from the upper portion of the zone, accumulating condensate from an intermediate portion of the zone, reheating the condensate to a constant temperature, returning the reheated condensate to the lower portion of the zone at a constant rate, condensing the withdrawn vapors, returning a portion of the condensed vapors to the zone as reflux, and controlling the return of reflux by the level of the accumulated condensate.

2. The method of fractionating hydrocarbon vapors, which comprises passing the vapors

constituents of the vapors are condensed, withdrawing uncondensed vapors from the upper portion of the zone, accumulating condensate from another portion of the zone, reheating the accumulated condensate to a constant temperature, returning the accumulated condensate to the lower portion of the zone at a constant rate, withdrawing a side stream of condensate from the zone, and controlling the amount of the side stream by the level of the accumulated condensate.

3. The method of fractionating hydrocarbon vapors, which comprises passing hydrocarbon vapors through a fractionating zone whereby heavier constituents of the vapors are condensed, withdrawing uncondensed vapors from the upper portion of the zone, accumulating condensate from an intermediate portion of the zone, returning the condensate to the lower portion of the zone, reheating the returning condensate, condensing the withdrawn vapors, returning a portion of the condensed vapors to the zone as reflux, controlling the return of reflux by the level of the accumulated condensate, and withdrawing bottoms from the zone.

4. Apparatus for fractionating hydrocarbon vapors, which comprises a fractionating column, means for introducing vapors into an intermediate portion of the column, means for withdrawing uncondensed vapors from the upper portion of the column, a shell for accumulating condensate from a lower portion of the column, means for condensing the overhead vapors and for returning a portion of the condensate to the upper portion of the column, means actuated by the level of liquid in the shell for controlling the return of reflux, and means for reheating the accumulated condensate.

5. Apparatus for fractionating hydrocarbon vapors, which comprises a fractionating column, means for withdrawing uncondensed vapors from the upper portion of the column, a shell, means for conducting condensate from the lower portion of the column to the shell, a line for conducting condensate from the side of the column, means controlled by the level of liquid in the shell for regulating the flow through the line, means for reheating the condensate withdrawn from the shell, and means for reintroducing the reheated condensate in constant quantities into the column.
